CEILING PAPER HANGER

Clifton L. Brockmann, Coquille, Oreg.

Application June 13, 1946, Serial No. 676,421

8 Claims. (Cl. 216—7)

1

This invention relates to a ceiling paper hanger or device especially adapted for use by amateur paper hangers for hanging ceiling paper, and comprises a novel device to which the paper is applied after being pasted and the ends folded over, for supporting the paper in the direct line in which the same is to be pasted or applied to the ceiling, and for greatly facilitating the hanging of the paper by simply moving the device along the ceiling to cause the paper to unfold and be pressed thereagainst, so as to be applied and adhere thereto.

Another object of the invention is to provide a ceiling paper hanger in the form of a frame having means for connecting one end of the folded paper after being pasted, thereto, constituting the starting point by which the end of the paper is applied to the ceiling in hanging the same, and a brush or pressure device at the opposite end to smooth the paper and press the same against the ceiling, so as to cause the same to be smoothly applied in a straight line, whereby the strip of paper will be applied along one edge of a ceiling and the next adjacent strip in line with the opposite edges of the previously applied strips.

Another object of the invention is to provide a ceiling paper hanger which is of very simple construction, light in weight and which will greatly facilitate the hanging of paper on a ceiling, without previous experience, quickly and properly.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of a ceiling paper hanger constructed in accordance with the present invention.

Figure 2 is a plan view of another form of ceiling paper hanger partly broken away and in section.

Figure 3 is an enlarged fragmentary sectional view taken on the line 3—3 of Figure 2.

Figure 4 is a side elevation of the device shown in Figure 2.

Figure 5 is a sectional view taken on the line 5—5 of Figure 2.

Figure 6 is a sectional view of the device shown in Figure 1, showing the method of applying or hanging the ceiling paper by means thereof, and

Figure 7 is a perspective view of a pressure applying means with a brush, adapted for use at one end of the frame of the ceiling paper hanger.

2
Referring to the drawings in detail, in which like reference characters designate corresponding parts throughout the several views, the ceiling paper hanger is shown as comprising a frame generally of rectangular form, having longitudinal parallel side members 10, shown in Figure 1 as of circular cross-section, such as one inch round stock wood or the like, although any other suitable material may be employed. The forward ends of the side members are connected by a pressure applying member 11 constituting a smoothing member or block for the paper running transversely and connected to the forward extremities of the side members 10, and may be provided with a brush 12 extending around part of the circumference or upper side thereof, the member 11 being shown as circular and suitably joined at its ends to the forward ends of the side members 10. At the rear, the rear ends of the side members 10 are connected by a rear transverse connecting member or end member 13 also formed in circular cross-section and of the same stock material or otherwise, as the members 10. The rear transverse connecting cross member 13 is shown provided on its lower surface with a plurality of curved pins or nails 14, preferably four in number equidistantly spaced apart, near but slightly spaced from the ends thereof, and at intermediate points on either side of the center and projecting downwardly in curved radial formation inwardly for a purpose to be hereinafter explained.

35 Lying centrally and longitudinally between the end members 11 and 13, is a longitudinal intermediate member 15, parallel to the side members 10 and which has its ends connected to the ends of the members 11 and 13 as shown, by means of suitable sockets, glued or otherwise fastened thereto rigidly. This member 15 forms the handle of the device, in use.

40 In the use of the device, as shown in Figure 6 of the drawings, the strip of paper to be hung is pasted in the usual way upon the reverse side, and the ends folded over so that the frame of the hanger is spaced upon one end portion about a half inch from the end edge thereof, which end is folded over the rear cross member 13 and hooked over the bent pins or nails 14 constituting retaining or anchoring means for the end of the paper thereto. The device is then reversed in position and with a suitable scaffolding or support upon which the operator may reach the ceiling, and with the paper upon the top of the frame in the folded condition as explained, the end which is anchored to the cross member 13

is placed up against the end of the ceiling and pressed against the same to adhere thereto, and pressed by a brush or the hands between the member or end 13 and felt member or brush 12 to stick or adhere to the ceiling and to line up one longitudinal side edge of the paper with or along one side edge of the ceiling or vertical wall of a room and by disengaging, tearing or pulling the pins 14 loose from the paper with a slight pull of the frame along the ceiling and downwardly, the paper will pull free of the pins, the device is advanced across the ceiling to carry the depending portion of the strip therewith or merely smoothed out and pressed against the ceiling with a brush, so as to cause the paper to adhere to the ceiling at the pasted side of the paper. In doing this, the frame of the hanger is grasped by the longitudinal handle forming member 15 and the weight of the paper will draw itself tight over the frame suspended from the pressure strip, block or smoothing member 11, having a curved pressure surface with a soft covering of felt or cloth if desired, or provided with the brush 12 over which the unpasted side of the paper extends so as to hang downwardly therefrom into the room as shown in Figure 6. With the end 13 against the wall line edge of the paper and against the ceiling, or along the edge of a previous strip, the frame is held firmly against the paper at the ceiling and after disengagement, tearing loose or lifting off of the pins 14 at and from the adjacent end "A" of the paper, runs smoothly so that the pressure member or smoothing block or brush at the opposite end is also applied against the ceiling with proper pressure, gripping the end 11 if desired, in connection with the gripping of the portion 15 or 15' with the other hand. Of course, it is necessary to disengage the pins 14 from the anchored end of the paper A and lower or swing the end 13 downwardly in order to move the frame and smoothing bar or brush 12, 20 or 24 firmly pressing the same against the ceiling so as to smoothly press or brush the paper against the ceiling for a distance of about two feet. Continued advancement of the bar or brush against the paper to cause the same to be pressed against the ceiling will cause the paper to unfold as it is applied, until the entire strip of paper has been stretched across and applied to the ceiling to the other end. In the drawings, in Figure 6, the anchored end is indicated at A, attached to the curved pins or nails 14 and end A, is freed therefrom as soon as the adjacent end is caused to adhere to the surface of the ceiling and the adjacent vertical wall portion B, the ceiling being designated at C. The paper D then extends over the frame and the pressure applying end, brush or bar with the soft covering of cloth or felt, or the brush 12 as described, so that the folded opposite end of the paper is suspended therefrom, the fold being designated at E, with the adjacent end adhered thereto in the folded condition as indicated at F. By this means, the paper may be hung on the ceiling by an amateur quickly and accurately, to provide a smooth papering job.

In the form of the invention shown in Figures 2, 3, 4 and 5, the frame is of the same identical rectangular form, except that the sides are made of flat strips, as indicated at 16, fastened to the end member 13 as indicated at 17 by means of screws or other fastening means applied outside of the ends of the rear cross member 13. The central member 15' corresponds to the mem-

ber 15 and is connected to an additional cross member 18 spaced rearwardly from the forward ends of the side strip members 16 of the frame and to which the forward end of the central handle-bar 15' is anchored as previously described in connection with the central handle-bar 15. The strips 16 at the sides are also attached to the ends of the cross member 18, in the same manner as they are connected to the end member 13 and as indicated at 17.

The forward extremities of the sides 16 beyond the cross members 18, and indicated at 19, are arranged to carry a pressure bar or smoothing member, which may be in the form of a roller or other soft member, or brush 20, having journal ends 21 rotatably mounted in the end portions of the extensions 19, so as to turn when in use for applying the paper to the ceiling and hanging the same. This device is used in the same manner as the device shown in Figures 1 and 6 of the drawings.

In Figure 7 of the drawings, the brush or other soft felt or cloth pressure and smoothing member at the front, is shown comprising a strip or bar 22 having a convex edge 23 provided with the soft covering, which may consist of a felt strip 24, the width of which substantially extends around 180 degrees of the surface or circumference thereof. However, with either form of the device, the central longitudinal member forms a handle, while the member 18 not only forms a brace, but will also form as a handle at the front end of the frame, in lieu of the members 11 or 22, either of which may be provided with a suitable hand-grip for the purpose, in order to facilitate application of the paper in hanging the same against the ceiling. The device is of very simple construction and can be economically produced in quantities, in addition to being extremely light and easily handled by an amateur for efficiently and properly applying or hanging paper to a ceiling as described.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

1. A ceiling paper hanger comprising a frame member having sides and end members connected at their extremities, one end member having a plurality of paper piercing and engaging members spaced along the same for attaching one end of a pasted strip of paper in folded position thereto to extend over the same in applying the same to a ceiling with the frame substantially parallel to the ceiling surface and the other end of the paper extending over the opposite end of the frame, said latter end having a soft surface for smoothing and pressing the paper against the ceiling by detaching the opposite end of the frame from the paper and moving the frame along the ceiling and paper in an upward pressure.

2. A ceiling paper hanger comprising a rectangular frame having a handle member running longitudinally and centrally thereof, a cross member at one end, a plurality of downwardly and inwardly curving pins carried by said cross member adapted for anchoring one end of a strip of pasted and folded paper to be hung thereover to be pierced by said pins, so that the paper extends over the top of the frame, and a cross bar at the opposite end of the frame having a soft covering

thereon over which the other folded end of the strip of paper to be hung extends to be moved along the paper at the undersurface thereof for applying pressure and smoothing the paper as pressed against the ceiling after detaching the opposite end of the paper from the pins.

3. A ceiling paper hanger comprising a rectangular frame having a handle member running longitudinally and centrally thereof, a cross member at one end, a plurality of downwardly and inwardly curving pins carried by said cross member adapted for anchoring one end of a strip of pasted and folded paper to be hung thereover to be pierced by said pins, so that the paper extends over the top of the frame, and a cross bar at the opposite end of the frame having a soft covering thereon over which the other folded end of the strip of paper to be hung extends to be moved along the paper at the undersurface thereof for applying pressure and smoothing the paper as pressed against the ceiling after detaching the opposite end of the paper from the pins, said cross member having the soft surface being in the form of stiff bristles to form a brush.

4. A ceiling paper hanger comprising a rectangular frame having a handle member running longitudinally and centrally thereof, a cross member at one end, a plurality of downwardly and inwardly curving pins carried by said cross member adapted for anchoring one end of a strip of pasted and folded paper to be hung thereover to be pierced by said pins, so that the paper extends over the top of the frame, and a cross bar at the opposite end of the frame having a soft covering thereon over which the other folded end of the strip of paper to be hung extends to be moved along the paper at the undersurface thereof for applying pressure and smoothing the paper as pressed against the ceiling after detaching the opposite end of the paper from the pins, said cross member having the soft surface being in the form of a brush of curved formation extending upwardly in the direction opposite to the direction of extension of the pins.

5. A ceiling paper hanger comprising a rectangular frame having a handle member running longitudinally and centrally thereof, a cross member at one end, a plurality of downwardly and inwardly curving pins carried by said cross member adapted for anchoring one end of a strip of

pasted and folded paper to be hung thereover to be pierced by said pins, so that the paper extends over the top of the frame, and a cross bar at the opposite end of the frame having a soft covering thereon over which the other folded end of the strip of paper to be hung extends to be moved along the paper at the undersurface thereof for applying pressure and smoothing the paper as pressed against the ceiling after detaching the opposite end of the paper from the pins, said cross member having the soft surface being in the form of a brush rotatably mounted at said end.

6. A ceiling paper hanger comprising a frame 15 having parallel side members, a cross member at one end, paper anchoring and piercing means extending downwardly and inwardly of said end, a central longitudinal handle member and a cross member at the other end comprising a relatively smooth pressure applying and smoothing bar.

7. A ceiling paper hanger comprising a frame having parallel side members, a cross member at one end, paper anchoring and piercing means extending downwardly and inwardly of said end, a central longitudinal handle member and a cross member at the other end comprising a pressure applying member at the top of convex cross-section forming a hand gripping member.

8. A ceiling paper hanger comprising a frame 30 having parallel side members, a cross member at one end, paper anchoring and piercing means extending downwardly and inwardly of said end, a central longitudinal handle member and a cross member at the other end comprising a pressure applying member at the top of convex cross-section 35 and another cross member connecting the side members and connected to the forward end of the central longitudinal member in spaced relation rearwardly of the forward cross member 40 constituting the cross-member second named.
